(57) **CLAIM**

I claim the new, original, ornamental design for a harp mounting system, as shown.

DESCRIPTION

FIG. 1 is a perspective view of the harp mounting system;
FIG. 2 is a front end view of the harp mounting system;
FIG. 3 is a right side view of the harp mounting system, the
left side view being a mirror image thereof; and,
FIG. 4 is a top view of the harp mounting system, the bottom
view being a mirror image thereof.
